DESIGN FOR A PINCH TYPE HEAT SEALER

Carl Usinger, Wauwatosa, Wis.

Application November 26, 1943, Serial No. 111,796

Term of patent 14 years

(Cl. D26—1)

To all whom it may concern:

Be it known that I, Carl Usinger, a citizen of the United States and resident of Wauwatosa, in the county of Milwaukee and State of Wisconsin, have invented a new, original, and ornamental Design for Pinch Type Heat Sealer, of which the following is a specification, reference being had to the accompanying drawing, forming part thereof.

Fig. 1 is a side elevational view of a pinch type heat sealer showing my new design;

Fig. 2 is a bottom plan view of the pinch type heat sealer shown in Fig. 1; and

Fig. 3 is a front elevational view of the pinch type heat sealer shown in Fig. 1.

I claim:

The ornamental design for a pinch type heat sealer, as shown.

CARL USINGER.
